UNITED STATES PATENT OFFICE.

GEORGE R. MOON, OF COLUMBUS, OHIO.

BAKING-OVEN.

SPECIFICATION forming part of Letters Patent No. 658,188, dated September 18, 1900.

Application filed August 2, 1900. Serial No. 25,624. (No model.)

To all whom it may concern:

Be it known that I, GEORGE R. MOON, a citizen of the United States, residing at Columbus, in the county of Franklin and State of Ohio, have invented a certain new and useful Improvement in Baking-Ovens, of which the following is a specification.

My invention relates to an improvement in baking-ovens of that class which are adapted for use in conjunction with gasolene or gas stoves or burners, and has particular relation to the improvement of the construction set forth in my former patent, No. 598,570, issued under date of February 8, 1898.

15 The objects of my present invention are to provide a baking-oven of the class mentioned with improved means for equalizing the circulation of heat through the various portions of the oven, to provide in conjunction therewith an improved heat-deflector, and to produce other improvements the details of construction of which will be more fully pointed out hereinafter. These objects I accomplish in the manner illustrated in the accompanying drawings, in which—

Figure 1 is a front view of my improved baking-oven. Fig. 2 is a sectional view on line *x x* of Fig. 1. Fig. 3 is a sectional view taken through the oven at right angles with that shown in Fig. 2. Fig. 4 is a sectional view on line *y y* of Fig. 1, and Fig. 5 is a view in elevation of a portion of one end of the oven-body.

Similar numerals refer to similar parts throughout the several views.

In carrying out my invention I employ, as set forth in my said former patent, an exterior casing 1, having suitable openings 1^a in its upper side, within which is arranged a casing 2. This inner casing does not extend across the bottom of the oven-body and is omitted from that portion of the front of said body in which is formed a doorway 3. This doorway is adapted to be closed by one or 45 more doors 4, the latter being preferably of double thickness, as shown. 5 represents a heat receiving and deflecting body which is supported in the lower portion of the oven-body and extends between opposite sides 50 thereof. This deflector, as indicated in the drawings, is in the form of a transversely-arranged triangular box, between the for-

ward vertical wall of which and the forward inner-casing wall is formed a vertical flue 6. The rear and smaller end of the deflector 5 terminates at a point at a desirable distance from the inner side of the rear vertical wall of the inner casing. Within the interior of the inner casing and extending between opposite sides thereof and the vertical walls 7 of a central flue 8 are arranged the desired number of shelves or horizontal baking-plates 9, each of which has its rear end provided with a downwardly-extending vertical plate 10, these plates extending between and connecting opposite side walls of the inner casing and the flue-walls 7 and having their lower terminations at the right or in rear of the triangular deflector 5. As indicated in the drawings, the vertical plates 10 are so arranged with relation to each other as to form between them and between the rear-most plate 10 and the rear vertical wall of the inner casing vertical flues, such as are indicated at 11 and 12. The inner plate 10, 75 as shown in the drawings, is so arranged with reference to the rear end of the deflector 5 as to leave a heat outlet or opening 10^a between the lower end of said inner plate and said deflector, this opening being of slightly-less 80 size than the flue-opening 11. These flues, which thus lead, respectively, from the lower portion of the oven-body to the open spaces above the shelves 9, are, as shown more clearly in Fig. 2 of the drawings, graduated in size— 85 that is, the inner and shorter flue 11 is of smaller size than the outer flue 12.

The vertical flue plates or walls 7 are, as indicated in Figs. 3 and 4 of the drawings, provided with perforations 13, through which 90 communication with the open spaces above the shelves and above the triangular deflector 5 is established with the central flue 8.

At opposite points in the side or end walls of the inner casing I provide the desired number of openings 14, said openings forming a communication between the interior of the inner casing and the flues 15, which are formed between said inner and outer casings. In each end of the inner casing I form an 100 opening 14^a, which leads into the interior of the deflector, and in the ends of the exterior casing I form similar openings 14^b.

Between the end or side walls of the inner

and outer casings 1 and 2 I provide, as indicated in section in Fig. 3 of the drawings and in dotted lines in Fig. 2, U or yoke shaped partitions 16, the latter inclosing, respectively, the groups of openings 14, which are above and below the upper shelves 9.

The bottom of the oven-body herein described is formed open or with a comparatively-large central opening therein, such as is indicated at 17.

In utilizing my invention the oven-body formed as above described is adapted to be seated over the burners of a gasolene or gas stove or other suitable heat-generating apparatus. The heat which rises therefrom comes into contact with the rearwardly and upwardly inclined under side of the deflector 5, the greater portion of the heat thus discharged following the incline of said deflector 20 and passing upward through the flues 11 and 12 and through the opening 10^a, thus being distributed into the oven-spaces which are below and above the shelves. In order that the greater quantity of heat will not be carried into the lower oven-spaces, I have graduated the size of the opening 10^a and flues 11 and 12 for the purpose of equalizing the distribution of heat through said opening and flues. It will readily be seen that this graduation is made necessary by the natural tendency of the heat to rise through the first openings or flues encountered after leaving the deflector. Through the construction described it is obvious that the heat will be 35 equally distributed within the oven-spaces and that the openings 13 in the central flue-walls will afford a means of communication between the flue 8 and said oven-spaces. From each of these oven-spaces the heat may 40 pass through the openings 14 into the flues 15 and out through the openings 1^a in the top of the outer casing. The forward vertical

flue 6 also affords a means of communication between the lower portion of the oven-body and the baking-spaces, thus providing, in conjunction with the opening 10^a and flues 11 and 12, a complete circulation of heat over the shelves.

Owing to the employment of the deflector, end openings 14^a, and the outer-casing openings 14^b, it will be seen that air from the outside of the oven-body may enter the deflector and becoming heated therein will pass upward through the flue 8 and thence into the oven-spaces, thus supplying the latter with an additional volume of hot air.

Having now fully described my invention, what I claim, and desire to secure by Letters Patent, is—

In an oven, the combination with a double-walled casing having a doorway therein and doors therefor and a triangular deflector-casing supported in the lower portion of the oven-body, of parallel shelves arranged one above the other above said deflector, plates 10 extending downward from the rear ends of said shelves, said plates being so arranged with relation to each other to the rear wall of the inner casing and to the rear end of the deflector as to provide an opening between the lower portion of the oven-body and the space below the lower shelf and flues leading respectively to the spaces above the shelves, said opening and flues being graduated in size as described, central oven partition-plates 75 7 having perforations therein and forming a central flue 8, the external casing being provided with outlet-openings 1^a and the internal casing provided with openings 14, substantially as specified.

GEO. R. MOON.
